GAME COUNTING DEVICE

Joseph D. McOsker, Allston, Mass.

Application December 28, 1937, Serial No. 182,135

4 Claims. (Cl. 235—80)

The invention relates to a counting device and more especially to a scoring device for games of cribbage or the like.

The primary object of the invention is the provision of a device of this character, wherein scoring for either the shorter or longer cribbage games may be effected without liability of confusing competing players of the game in the scoring of points thereof and minimizing the possibility of occurrence of mistakes, which generally result in disputes between the players, the board being formed with holes for the reception of scoring pegs or pins and such holes are arranged that the counting progress of the pegs or pins can be had in one general direction of the board and thus eliminating the necessity of reversing the course of the pins or pegs in the scoring of points thereby.

Another object of the invention is the provision of a device of this character, wherein the pin or peg holes are grouped in series having trends in separated scoring lanes for occupancy in the least possible space and without the necessity of increasing the length of the board of such device, which would be the case if the lanes were provided with straight rows of holes devoid of the zigzag arrangement and further the scoring pins or pegs can be manipulated in one general direction only for scoring purposes.

A further object of the invention is the provision of a device of this character, wherein demarcations are present at the scoring side of the board enabling determination at any stage in the progress of a game of the particular scoring at a glance, while other demarcations are present on the scoring side of the board indicative of starting points of scoring and identification of a winner of the game.

A further object of the invention is the provision of a device of this character, wherein the construction thereof allows for the storing of the scoring pins or pegs when not in use while at the scoring side of the board are racks for the scoring pins or pegs to hold the same conveniently accessible for scoring on the starting of the game.

A still further object of the invention is the provision of a device of this character, which is simple in construction, thoroughly reliable and efficient in operation, assuring against confusion, mistakes and disputes in the scoring when playing a game of cribbage or the like and inexpensive to manufacture.

With these and other objects in view, the invention consists in the features of construction, combination and arrangement of parts as will be

hereinafter more fully described, illustrated in the accompanying drawing, which discloses the preferred embodiment of the invention and pointed out in the claims hereunto appended.

In the accompanying drawing:

Figure 1 is a top plan view of the device constructed in accordance with the invention.

Figure 2 is a side edge elevation partly in section showing a scoring pin or peg engaged.

Figure 3 is an end edge elevation of the device with pins or pegs in scoring position thereon.

Similar reference characters indicate corresponding parts throughout the several views in the drawing.

Referring to the drawing in detail, A designates generally a flat faced board and its body 10 is preferably of substantially rectangular shape having at one working face thereof and formed therein a scoring field 11 involving a plurality of lanes created by groups of spaced socket-like openings or holes 12, the lanes being indicated at 13 and the holes or openings 12 are disposed zig-zag throughout the said lanes which are longitudinally directed with respect to the length of the body 10 of said board A.

These holes or openings 12 removably accommodate scoring pins or pegs 14, which normally are stored within a pocket 15 provided in the body 10 and opening through one end thereof, the open end being closed by a pivoted closure 16 adapted when in closing position to be latched at 17.

The field 11 of the board body 10 has provided thereon spaced lines 18, being disposed transversely of the lanes 13 for grouping arrangement of the holes or openings 12 into independent groups in the respective lanes so that participants in the game of cribbage, when scoring by the use of the pegs or pins 14 through engagement thereof in the holes or openings 12, can readily discern a score at determined intervals in the progress of the game. The zigzag disposition of the holes or openings 12 will allow scoring to be effected in one general direction of the board and also avoids the use of a longer board, which would be the case if these holes or openings were disposed in straight rows. The three-lane arrangement of the holes or openings 12 permits of a three-handed game of cribbage scoring.

At opposite ends 19 of the board body 10 are provided spaces 20, one of the latter being provided with pairs of spaced holes 21 and the other the spaced single holes 22, respectively.

Medially of the scoring field 11 there is a demarcation 23, being transversely of the board

A for the purpose of dividing the scoring field 11 so that the board A is usable for the playing of the longer or shorter games of cribbage in the scoring of points, the longer game involving one hundred and twenty-one scoring points while the shorter game involves sixty-one scoring points as usual. When playing the shorter game, the start in scoring is from the line of demarcation 23 progressively in each lane toward the zone 20 having the single holes or openings 22 therein, being the finishing end of the board, while in the playing of the longer game the scoring is had from the zone 20 with the pairs of holes 21 therein, the finish of the longer and shorter games being effected at the zone 20 having the single holes or openings 22 therein.

By the arrangement of the holes or openings 12 in each lane in a zigzag disposition, a scoring by a player assigned a lane 13 can be had in one general direction and in this manner there is avoided the reversing of the course of scoring operation in the handling of the pegs or pins 14 without confusion to the players or mistakes being made on their part leading to disputes with respect to scorings.

The holes 21 at one end 19 of the board A are merely for the purpose of racking the scoring pins 14 prior to the use thereof for scoring purposes and the space in the zone 20 occupied by the holes 22 is the finishing zone for scoring purposes in either of the shorter or longer games of cribbage.

What is claimed is:

1. A device of the kind described comprising a board proper of elongated formation and having a flat scoring field provided with independent spaced rows of holes such holes being arranged zigzag within a straight path to opposite ends of the row in one direction only for effecting spaced parallel lanes, each line of the zigzag including a plurality of holes, pegs engageable in said holes for counting purposes, starting and finishing zones at opposite ends of the lanes and having racking and finishing holes, respectively, lines of demarcation disposed transversely of the lanes and dividing the holes into a plurality of groups.

2. A device of the kind described comprising a board proper of elongated formation and having a flat scoring field provided with independent spaced rows of holes such holes being arranged zigzag within a straight path to opposite ends of the row in one direction only for effecting spaced parallel lanes, each line of the zigzag including a plurality of holes, pegs engageable in said holes for counting purposes, and starting and finishing zones at opposite ends of the lanes and having racking and finishing holes, respectively.

3. A device of the kind described comprising a board proper of elongated formation and having a flat scoring field provided with independent spaced rows of holes such holes being arranged zigzag within a straight path to opposite ends of the row in one direction only for effecting spaced parallel lanes, each line of the zigzag including a plurality of holes, pegs engageable in said holes for counting purposes, starting and finishing zones at opposite ends of the lanes and having racking and finishing holes, respectively, and lines of demarcation disposed transversely of the lanes and dividing the holes into a plurality of groups.

4. A device of the kind described comprising a board proper of elongated formation and having a flat scoring field provided with independent spaced rows of holes such holes being arranged zigzag within a straight path to opposite ends of the row in one direction only for effecting spaced parallel lanes, each line of the zigzag including a plurality of holes, pegs engageable in said holes for counting purposes, starting and finishing zones at opposite ends of the lanes and having racking and finishing holes, respectively, lines of demarcation disposed transversely of the lanes and dividing the holes into a plurality of groups, and a line of demarcation carried transversely of the scoring field of said board proper at the median thereof.

JOSEPH D. MCOSKER.
